UNITED STATES PATENT OFFICE

JAMES L. SHANNON, OF LONGMEADOW, MASSACHUSETTS

DESIGN FOR A FLASH-LIGHT CASING

Application filed October 17, 1930. Serial No. 37,280. Term of patent 14 years.

To all whom it may concern:

Be it known that I, JAMES L. SHANNON, a citizen of the United States, residing at Longmeadow, in the county of Hampden and State of Massachusetts, have invented a new, original, and ornamental Design for Flash-Light Casings, of which the following is a specification, reference being had to the accompanying drawing, forming part thereof.

The figure is a side view of a flashlight casing, showing my new design.

I claim:

The ornamental design for a flashlight casing, as shown.

JAMES L. SHANNON.
